UNITED STATES PATENT OFFICE.

ROBERT H. LINDSAY, OF HOUSTON, TEXAS.

DEHYDRATOR.

Application filed February 6, 1925. Serial No. 7,397.

My invention relates to dehydrators adapted to remove the water and other impurities from crude petroleum.

Crude petroleum, as it comes from the well, is frequently found emulsified with water, basic sediment and other similar impurities. The oil and water are so intimately mixed that they will not settle out on standing, except when specially treated by electricity, heat, chemicals, or the like. The cost of treating the oil is a material item of expense necessary in obtaining oil free from its emulsion of water.

It is an object of my invention to provide an apparatus for treating the crude oil as it comes from the well, whereby the impurities may be removed in a simple and economical manner. It is also desired that the process of separation shall be a continuous one, so that a continuous stream of the cut oil may pass through the device for purification without intermissions or delays.

My invention involves warming the crude oil to a temperature of approximately 150° Fahrenheit and maintaining it at about that temperature and allowing the oil and water to expand in an open pan subjected to the action of the air. This will cause the water particles to expand and coalesce and unite to form larger particles which will separate by gravity; carrying off also such other impurities as there may be in the oil.

In carrying out this process, I employ a furnace of which Fig. 1 is a broken central vertical section. Fig. 2 is a transverse section on the plane 2—2 of Fig. 1. Fig. 3 is a horizontal section of the furnace looking down upon the oil pipes. Fig. 4 is a top plan view with the upper wall partly broken away. Like numerals of reference are employed to designate like parts in all the views.

The furnace may be of any approved construction. The drawing illustrates one of approximately rectangular form, having its forward wall 1 formed with an opening 2 leading to a firebox 5. Said opening is normally closed by a cover or door 3. Below the door an oil burner pipe 4 extends through the wall, terminating within the firebox, in a burner nozzle 6. Directly in front of said nozzle is a firewall or baffle 7 of heat resisting material. The flames and heated gases from the firebox pass over the upper forwardly inclined firewall and then rearwardly to the chimney 8.

In the upper end of the furnace is a pan or plate 9 which is of the full width of the furnace. At the forward end of the pan adjacent the front wall of the furnace, I provide a trap 10, formed by a U shaped curve in the bottom wall of the pan with a wall or partition 11 secured to the upper wall 12 of the furnace and extending downwardly centrally of the curved wall 10. At the lower end of said trap may be provided an outlet or drain pipe 13, which, as shown in Fig. 2, extends laterally through the side wall of the furnace and may lead to any means for disposing of the waste thus drained off.

The pan 9 is supported by transverse bars 15 arranged at suitable intervals, and the length of the furnace and pan may be arranged as found necessary. Throughout the length of the pan I arrange traps 10 similar to the one just described, and the pan and upper wall of the furnace will incline downwardly from the front to rear of the device so as to carry the oil by gravity to the rear end where it may be discharged through an outlet pipe 16, to storage.

The cut oil will be heated before it is run into the pan 9 and this may be accomplished by passing it through a pipe 17 which enters the front wall of the furnace at 18 and is recurved back and forth as shown in Fig. 3 below the pan 9 and is again extended out through the forward wall at 19 and curved upwardly and over the front furnace wall to discharge into the pan at the forward trap 10.

The pipe 17 is supported on transverse supporting bars 21 at a point in the furnace directly within the path of the heated gases passing from the firebox to the chimney. It is provided at its forward end with a valve 22 by which the amount of oil passing through the said pipe may be regulated.

The oil, in passing through the traps and over the pan 9, will be forced through a small filter 23 in each of the said traps. This filter, or strainer, may be of gauze or some finely divided material serving to assist in breaking up the water and sediment within the oil so that it will better settle out.

In order to subject the oil in its passage over the pan to the effect of the atmosphere, I have provided openings 24 in the side wall of the furnace spaced above the pan a material distance above the level of the oil. The air which finds entrance through said openings will pass along the surface of the

oil and be discharged upwardly through the pipes 25 adjacent each of said traps. The heated air above the oil will tend to rise and be discharged through the pipes 25, thus causing a draft inwardly through the openings 24 of fresh air during the operation of the device. This draft of air across the surface of the oil may be accelerated by blowers or otherwise, if desired.

10 The operation of the device will now be clearly understood. The oil having been heated in the pipe 17 will be discharged into the pan at the forward end of the furnace. The pan and the traps will be heated by the gases from the furnace, and will maintain the oil at the desired temperature at all times, and it is contemplated that the intensity of the heat will be regulated as desired by means of the burner 4. The oil having been heated in the pipe 17 and discharged into the open space in the trap 10, will expand and the water will tend to at once separate from the oil, and such portion of the water as is thus separated from the oil will settle to the lower end of the trap and may be drawn off through the pipes 13. The passage of the oil through the filter 23 will assist in breaking up the oil and water and will also prevent the passage of the larger grains of sediment or sand which may be passing through with the oil.

15 20 25 30

As the oil flows along the pan 9 it will be heated further from contact with the surface of the pan and will be allowed to spread out and expand fully under atmospheric pressure. The passage of the air along the surface of the oil assists in the separating of the impurities from the oil in that it carries away any gases which arise from the oil and supplies free opening for the entrance of fresh air at all times.

It is contemplated that the inclination of the pan shall be such as to cause the oil to flow slowly by gravity from one end of the pan to the other, and that in its passage through the separate traps arranged along the pan all the water and basic sediment, will gradually drain off through the pipes 13 so that when the oil issues through the pipe 16, it will be entirely free from its impurities.

In the use of this device the flow of impure oil into the apparatus may be continuous, and during its passage therethrough all the impurities therefrom will be eliminated, and the speed of flow of the oil through the device may be regulated to ac-

cord with the amount of impurities in the oil being treated.

It is contemplated that the number of traps and the amount of inclination in the pan will be determined by experiment so that the oil will be entirely freed of its impurities when it issues from the device. The efficiency of the apparatus appears to lie largely in the fact that the oil is exposed in a thin film, as it passes over the surface of the pan 9 to the action of the air and that it is allowed to expand freely while thus heated. This is a great improvement over the heating of oil in pipes alone, where it is not thus free to expand. The operation of the apparatus has been found to be very efficient and to be cheap and economical in construction.

Having thus described my invention, what I claim as new, and desire to protect by Letters Patent is:

1. In an apparatus of the character described, a furnace, a firebox therein, a rearwardly inclined pan at the upper end of said furnace, means to feed heated oil to the upper end of said pan, traps arranged to extend downwardly into said fire box at spaced intervals along said pan, means to draw off liquid from the lower ends of said traps, and filtering means in said traps to assist in separating the impurities from the oil, there being means to allow a draft of air across said pan.

2. In an apparatus of the character described, a furnace, a shallow pan inclined rearwardly above said furnace, oil conducting pipes in said furnace below said pan, means to discharge oil from said pipes into the upper end of said pan, means to regulate the flow of oil to a thin film on said pan, said pan being open to expose said film of oil to the atmosphere, and means to draw off the impurities from said oil as it flows along said pan.

3. In a device of the character described, a furnace, a shallow inclined pan above said furnace, means to discharge heated oil at the upper end of said pan, traps arranged below the bottom of said pan to draw off impurities from said oil, means in said pan to direct the oil through said traps, and means at the lower end of said pan to receive the oil from said pan.

In testimony whereof I hereunto affix my signature this 26th day of January, A. D. 1925.

ROBERT H. LINDSAY.
